UNITED STATES PATENT OFFICE.

FREDERICK BENNETT, OF NEW YORK, N. Y., ASSIGNOR TO THE HALE AND KILBURN MANUFACTURING COMPANY, OF PHILADELPHIA, PENNSYLVANIA, A CORPORATION OF PENNSYLVANIA.

CHAIR.

SPECIFICATION forming part of Letters Patent No. 763,656, dated June 28, 1904.

Application filed February 14, 1902. Serial No. 94,056. (No model.)

To all whom it may concern:

Be it known that I, FREDERICK BENNETT, a citizen of the United States, residing in the borough of Queens, city of New York, State 5 of New York, have invented a certain new and useful Improvement in Chairs, of which the following is a description.

The object of the present invention is to provide a chair having a seat and a back (preferably, although not necessarily, separable) which shall be movable relatively to each other and to the supporting-frame and which by a slight shifting of the weight of the user may be so moved with relation to each other 15 as that the chair shall adapt itself to any desired sitting or reclining position of the user.

A further object of the invention is to so mount and position the seat and back as that although the inclination of each will change 20 with relation to the other, or the inclination of the back only will change with relation to the seat, the distance between a given point upon one and a given point upon the other shall be maintained substantially unchanged.

25 A further object of the invention is to so mount and support the seat and back within a suitable chair-frame as to secure the greatest durability of the various chair parts in operation, such parts being but few and of simple construction.

In carrying out the invention I employ a chair-frame consisting, essentially, of two side members, preferably connected by cross-bars, said frame being provided at a point 35 below the intended location of the seat with shelves or tracks upon which the seat-cushion is movably supported. The seat-cushion is adapted to slide upon these shelves or tracks and may, if desired, be provided with rolls 40 or sheaves to facilitate the sliding operation. The inner surface of each of the side frames is provided with a groove or track the upper portion of which is arranged in one plane and the lower portion at an angle to such upper 45 portion, and with such grooves or tracks coact studs or rolls secured to the edges of the seat-back. As said seat-back is moved down-

wardly the studs or rolls engaging with such tracks force the back to assume a position oblique to the plane of the seat, and as the 50 movement progresses the degree of inclination of such back is increased to the desired extent. In order that there may be no undue separation between the lower surface of the seat-back and the inner edge of the seat-cushion, the latter is provided with a sliding connection with such back, thus maintaining the 55 relativity between said seat cushion and back in any position in which these parts are adapted to be moved.

The parts above referred to are so constructed and arranged as that the power necessary to shift both the seat and the back in order to cause the latter to incline even more than normally with respect to the seat may 60 readily be supplied by a mere shifting of the weight of the occupant of the chair. The power so supplied will also be sufficient to return the chair seat and back to normal position by the same shifting operation on the 65 part of the user, but in the opposite direction. If desired, in order to more readily restore the chair to normal position the back thereof may be provided with a spring, the tendency of which is to produce this result.

70 The invention is illustrated in the accompanying drawings, in which—

Figure 1 is a central vertical section of a chair employing my invention, the cushion and back thereof being shown in dotted lines. 75 Fig. 2 is an end view of a portion of the chair illustrated in Fig. 1; and Fig. 3 is a central vertical section similar to Fig. 1, but illustrating the seat and back as moved to the extreme of the reclining position.

80 Referring to the drawings, in which similar letters denote corresponding parts, the chair-frame comprises the side members A, which may of course be of any suitable design. The rear portion of such frames, however, should extend sufficiently high to permit of the arrangement therein of guide-tracks 85 for the back, as hereinafter referred to. The side frames are here shown as connected by

cross-bars a' , and between such cross-bars extend seat-supporting bars a^2 . Of these there may be two or such other number as may be desired. It is not essential that these 5 parts be located intermediate of the side frames A, as I may, if desired, provide for the support of the seat by means of shelves extending inwardly from each of the side frames A. Such seat-supporting bars or 10 shelves will, as indicated herein, preferably be inclined, the outer end thereof (the front of the chair) being higher than the inner end.

B designates the seat or cushion. This is mounted to slide upon the bars a^2 and may, if 15 desired, be provided with rolls or sheaves b in order to facilitate the sliding operation. The seat, as here shown, is provided with two such sheaves, one for each of the seat-supporting bars a^2 . It is obvious, however, that there 20 may be a greater number of such sheaves, if desired. The rear edge of the cushion B instead of being parallel with the forward edge thereof preferably recedes sharply for the purpose of affording maximum space at that 25 point for the operation of the seat-back, as hereinafter described.

C designates the seat-back. This may be of any desired shape upon its operative surface and will, like the seat B, preferably be 30 upholstered. Secured to each edge of the back C and preferably in a line parallel with the longitudinal axis thereof are studs or rolls c . If rolls be employed, as herein shown, they may be carried on pivots c' . These rolls 35 contact with a groove or track D in each of the side frames A of the chair. As clearly shown in Figs. 1 and 3, the upper portion D' of each groove or track D is substantially straight and is arranged generally in or parallel to the 40 longitudinal axis of the seat-back when the same is in normal slightly-inclined position. The lower portion D^2 , however, extends at an angle to the portion D' in order that when the lower roll c^2 upon each side of the seat-back enters and is guided in the said portion 45 D^2 of such groove or track not only will the back be moved to a greater degree of inclination, but in effecting this movement the lower edge thereof will be brought forward 50 toward but below the rear edge of the seat B.

E designates a plate secured to each of the side edges of the back C. For simplicity of construction the lower stud or roll c^2 upon each side edge of the seat-back is preferably 55 secured to such plate, although this is not essential. Said plate E is provided with an elongated slot e' , which, as here shown, is arranged at an angle to the longitudinal axis of the back C, and therefore to that of the upper portion D' of the groove or track D. With each of the elongated slots e' coacts a stud f , secured to or formed integral with 60 one end of a bracket F, the other end of said bracket being secured to the side edge of the seat or cushion B. Said studs f may, if de-

sired, be provided with rolls for economizing friction and wear. When the parts are in normal position, as illustrated in Fig. 1, the studs f occupy their lowermost position in the slots e' of the plates E. As the back moves 70 downwardly and the upper portion thereof backwardly said studs rise in said slots until when the extreme reclining position is reached they occupy their uppermost position therein, as illustrated in Fig. 3. During this movement from one extreme position to the other the rear edge of the seat or cushion is kept nearly, or quite, in contact with the surface of the back, making, in effect, a continuous upholstered surface from the forward edge of 80 such seat to the top edge of such back. Also during the said movement from one extreme position to the other, the back being guided by the track D, the lower edge thereof passes downward as well as forward behind the rear 85 edge of the seat B, the latter also moving forward to permit this operation. As a result, although the inclination of the back is changed relatively to the seat, substantially no change takes place between a given point 90 on one and a similar point on the other. This feature conduces greatly to the ease and comfort of the occupant of the chair and precludes the disarranging of the clothing common in various prior constructions, including chairs 95 of the well-known Morris type. Another feature of importance is the ease and facility with which the adjustment of the chair to various positions may be effected by the shifting of the weight of the occupant. This applies to all positions of the chair from one extreme to the other. Thus, the parts being in the position illustrated in Fig. 1, rearward pressure against the back by the shoulders, involving as it does slight forward pressure 100 upon the seat by the limbs, readily moves such back and seat in the direction of the extreme position. (Illustrated in Fig. 3.) Cessation of the pressure at any point involves 105 cessation of movement of the seat and back. On shifting the body slightly forward the chair-back maintaining contact with the back and shoulders of the occupant will move to the desired extent toward the normal position. This operation is aided by a spring 110 suitably arranged to exert pressure upon the parts, tending to maintain them in the normal position. (Illustrated in Fig. 1.) I have here shown such a spring G, the rear end of 115 which is adjustably secured, by means of a hook or bolt g , to the cross-bar a' of the chair-frame, its forward end being connected to an arm H, secured to the lower end of the chair-back C and in the present instance extending downward and forward therefrom, 120 the said arm H aiding in guiding the back to its upright position.

If desired, the track D may be so arranged as to permit greater degree of movement of the chair-back and the seat (or either) than 130

herein described. In such case the shape or outline of the lower end of the back as well as that of the wearing-surface thereof may, if desired, be also modified.

5 What I claim is—

1. In a chair having side sections, the combination with a frame, having side sections and transverse supporting-bars, of a seat, an adjustable back, means for supporting and guiding the same comprising guideways on the side sections normally arranged substantially parallel to the back and having a forwardly-extended portion arranged at an angle to the seat, and means on the back for engaging the guideways, a plate carried by said back and having an elongated slot, an arm carried by said seat and having a pin or stud coacting with said slot, an arm extending downwardly and forwardly from the back, and a spring member on said arm secured to one of said transverse bars for normally holding said back in upright position, substantially as described.

2. In a chair having side sections, the combination with a frame, having side sections and transverse supporting-bars, of a seat, an adjustable back, means for supporting and guiding the same comprising guideways on the side sections normally arranged substantially parallel to the back and having a forwardly-extended portion arranged at an angle to the seat, and means on the back for engaging the guideways, a plate carried by said back and having an elongated slot, an arm carried by said seat and having a pin or stud coacting with said slot, said pin or stud being adapted to move in said slot with the movement of said adjustable back, an arm extending downwardly and forwardly from the back, and a spring member on said arm adjustably secured to one of said transverse bars for normally holding said back in upright position, substantially as described.

3. A chair, comprising a frame having side sections, and transverse and longitudinal supporting-bars, a slideable seat, rollers on the seat engaging the longitudinal supporting-bars, an adjustable back, guideways on the side sections normally arranged parallel to the back and having an upwardly-extended portion arranged at an angle to the seat, means on the back for engaging the guideways, a plate carried by said back and having an elongated slot, an arm carried by said seat and having a stud coacting with said slot, and a spring secured

to one of said transverse bars for retaining the back in normal position.

4. A chair, comprising a frame having side sections, and transverse and longitudinal supporting-bars, a slideable seat, rollers on the seat engaging the longitudinal supporting-bars, an adjustable back, guideways on the side sections normally arranged parallel to the back and having an upwardly-extended portion arranged at an angle to the seat, means on the back for engaging the guideways, a plate carried by said back and having an elongated slot, an arm carried by said seat and having a stud coacting with said slot, an arm extending downwardly and forwardly from the back, and a spring secured to the lower end of said arm and one of said transverse bars, for retaining the back in normal position.

5. A chair, comprising a frame having side sections, and transverse and longitudinal supporting-bars, a slideable seat, rollers on the seat engaging the longitudinal supporting-bars, an adjustable back, guideways on the side sections normally arranged parallel to the back and having an upwardly-extended portion arranged at an angle to the seat, means on the back for engaging the guideways, a plate carried by said back and having an elongated slot, an arm carried by said seat and having a stud coacting with said slot, an arm extending downwardly and forwardly from the back, a spring secured to the lower end of said arm and one of said transverse bars for retaining the back in normal position, and means for regulating the tension of the spring.

6. In a chair, the combination with a frame, of a seat, an adjustable back, means for supporting and guiding the same, comprising guideways on the side of the frame normally arranged parallel to the back, and having an upwardly-extended portion arranged at an angle to the seat, rollers on the back engaging the guideways, a plate carried by said back, an arm carried by the seat, a slideable connection between the arm and plate, a rod extending downwardly and forwardly from the back, and a spring member connecting said rod with the frame for normally holding said back in normal position.

This specification signed and witnessed this 105
13th day of February, 1902.
